LACE MEASURING MECHANISM

Joseph Fossa, South Hamilton, Mass., assignor to United Shoe Machinery Corporation, Flemington, N.J., a corporation of New Jersey

Original application December 19, 1952, Serial No. 326,948. Divided and this application May 26, 1958, Serial No. 737,646

5 Claims. (Cl. 12—58.5)

The present invention relates to improvements in a workholder for use in a machine for lacing shoe uppers and more particularly to an improved device for measuring the lengths of the laces passing through individual pairs of eyelets.

The invention is herein disclosed as embodied in a workholder for use in a machine for lacing shoe uppers having clamping devices for clamping the lacing margins of an eyeleted shoe upper in open-out edge-facing relation and a thread measuring finger or bar adapted to receive thereon groups of enchain lacings drawn through the eyelets of successive pairs.

This application is a division of applicant's copending application Ser. No. 326,948, filed in the United States Patent Office December 19, 1952, for Machine for Operating Upon Shoe Uppers.

In carrying out the invention a simple and improved mechanism is provided for supporting and for adjusting the position of the thread measuring finger employed in connection with the operation of the lacing mechanism to control the size of the several laces inserted in the eyeleted upper. In the illustrated construction the thread measuring finger is mounted on an arm which is pivotally supported for angular adjustment in a vertically adjustable bracket carried on the work support. Adjustments for height and for angle of the finger are made by means of two manually operable adjusting levers which are moved with relation to arcuate gauge scales carried on the vertically adjustable bracket. One of the adjusting levers is connected to control the vertical position of the bracket, the other lever being connected to control the angular position of the thread finger on its supporting arm. In the illustrated form of the invention the thread finger is supported in such a manner as to be readily lifted to permit the removal of the eyeleted and laced upper from the workholder. A thread finger of different length is readily substituted in the workholder for use in lacing shoe uppers of different types which may require the insertion of more lacings.

The several features of the invention will be readily understood by one skilled in the art from the following description taken in connection with the accompanying drawings in which:

Fig. 1 is a fragmentary plan view of an automatic machine for eyeleting and for lacing the eyeleted shoe upper illustrating particularly the work supporting and transfer assembly of the machine including the turret, one of the four workholders mounted thereon with an upper clamped therein, a second workholder in its open position, and a third workholder partially broken away to show underlying parts;

Fig. 2 is a view on front elevation of the turret and workholder assembly partly sectioned on a section line passing through the turret axis, two of the workholders disposed respectively at the eyeleting and unloading stations being shown;

Fig. 3 is an isometric view looking from below illustrating portions of one of the workholders, and the shoe

2

upper locating slide with the locating pins and fin slidably mounted on the workholder;

Fig. 4 is a fragmentary detail plan view of one of the workholder assemblies partly in section to illustrate particularly the lace measuring unit associated therewith; and

Fig. 5 is a sectional view in elevation of one of the workholder assemblies shown in Fig. 2 looking outwardly from the axis of the turret.

Referring to the drawings, the general arrangement of the improved machine disclosed for performing related eyeleting and lacing operations upon a shoe upper is generally indicated in the plan view, Fig. 1, and in the partly sectioned side view, Fig. 2, only so much of the machine, however, being shown as believed necessary to illustrate

15 the connection of the present invention therewith. For a more detailed disclosure of the machine, reference may be had to applicant's copending application above referred to and to the Fossa Patent No. 2,461,889, dated February 15, 1949, for Machine and Method for Manufacture of

20 Shoes. In the present disclosure, the base of the machine is generally indicated at 50 and includes a cylindrical casing 52 within which is mounted an indexing work supporting turret. The turret provides support for four workholders 132 which are mounted on guideways 131 extending radially outward from the turret at 90° angles from one another.

At the front side of the machine, there is provided a locating station which comprises a locating mechanism generally indicated at P for the assistance of the operator 30 in locating and clamping successive uppers on the workholders. At the remaining stations proceeding in a counterclockwise direction around the turret there are provided an eyeleting mechanism generally indicated I, a lacing mechanism generally indicated at L, and a fourth station between the lacing and loading station to which the workholding clamps are released.

Each workholder 132 of the illustrated construction, see Fig. 3, comprises a generally U-shaped member having outwardly flanged edges 135 forming guides which

40 ride under the recessed edges of the rail guideway 131, and two parallel sets of upwardly extending resiliently mounted pins 136 (see Fig. 2) which form the lower relatively stationary elements of a clamping device for engaging the two adjoining edge portions of the upper.

45 Each of the stationary clamping elements is formed toward its outer end with a laterally extending tab 137 which is particularly adapted to engage with and support the tongue portion of the shoe upper in a folded-over out-of-the-way position for the outside-up position of the upper on the workholder as shown, for example in Fig. 2.

50 The workholder 132 is formed with a vertically disposed post socket 138 (see Figs. 2 and 3) which projects downwardly from the closed end of the workholder adjacent the axis of the turret and is arranged to support for vertical adjustment therein a measuring bar support post hereinafter to be described. The socket 138 projects downwardly through the aperture formed by the channel 133 and separated rails of the guideway 131 and is freely movable therein with the workholder on the guideway 131.

55 Each workholder 132 as shown, for example in Fig. 1, has mounted thereon a pair of movable work clamping jaws 146, a pair of vamp spreaders 147, 148 and a lace measuring or slotting bar 149. The work clamping jaws

60 146 comprise a pair of lever arms which are supported intermediate their length on a pivot shaft 150 on the workholder 132 (see Fig. 2) and are connected at their rear ends to identical toggle links 151 which are pivotally connected to toggle arms 152 rotatably supported on a laterally extending pivot pin 153 at the rear end of the workholder 132. The toggle arms 152 are connected to turn as a single unit by a strap 154 arranged to be engaged

by an actuating lug 155 secured to the upper end of an axially movable control shaft 156 which is preferably connected to be moved downwardly by a treadle control, not here specifically shown.

Downward movement of the control shaft 154 causes the lug 152 to engage and depress the strap 154 to straighten the toggle links 151, 152 and thereby to effect a simultaneous movement of the clamping levers to clamping position. A small tension spring 157 connected between one of the clamping levers and work support tends normally to maintain the clamp in its open or disengaged position.

The work clamping jaws 146 are released prior to the final indexing movement which transfers the work support with the eyeleted and laced upper held thereon back to the loading station by means of an automatic release mechanism which is substantially similar to corresponding mechanism in the Fossa patent. The clamp release mechanism acts during the third indexing movement of the work support, i.e., during the indexing movement which serves to transfer the work support away from the lacing mechanism to a position at the left side of the machine, as indicated, for example, in Fig. 2. Clamp release plungers 162 are provided one for each work support journaled to slide in vertical drills in the turret 54 beneath the straps 154 of the clamp toggle connections, so that upward movement of any one of the plungers will cause the head thereof to engage and move the cooperating strap 154 upward to break the toggle connection, and thereby to release the toggle clamp. Substantially at the completion of each indexing movement of the turret 54 the plunger 162 associated with the workholder which has been moved to the position at the left of the loading station, is moved upwardly into engagement with the strap 154 to break the clamp toggle 151, 152 by the action of a slide 164 (see Fig. 2) supported for vertical movement in a relatively stationary guideway formed in a sleeve member 166 keyed to the fixed sleeve bearing element 62. For a description of the connections for raising the slide 164 and the contacting plunger 162 therewith which form specifically no part of the present invention reference may be had to the copending application above referred to.

In accordance with the invention, a novel mechanism is provided for supporting and for adjusting the position of the measuring bar 149. The mechanism shown has the advantage that it is readily adjustable by the operator in accordance with the lacing requirements of the particular upper being operated upon, is compact, and is so arranged on the workholder to permit the shoe upper including the heel portion thereof to be placed in the desired location on the workholder with either the inside or outside surface of the eyelet flaps facing upwardly as may be desired. As best shown in Figs. 2, 4, and 5, the lace measuring bar 149 is mounted on an arm 234 which is pivotally supported for angular adjustment on a horizontally extending bracket 235 mounted on a vertically adjustable post 236 which is axially shiftable in the socket 138 forming an integral part of the workholder 132. The bracket 235 carries a transversely disposed pivot pin 237 on which the arm 234 is mounted to turn. Two arcuate scales 238 and 240 are formed in a vertically disposed plate 241 mounted from the upper end of the post 236 for indicating respectively the position of angular adjustment of the arm 234 and the position of vertical adjustment of the lace measuring bar assembly including the post 236. For determining the angular position of the lace measuring bar 149, the arm 234 is extended rearwardly across a portion of the plate 241 opposite the scale 238 and is held in adjusted position in relation thereto by means of a small spring detent 242 which is spring pressed against a series of serrations 244 on the plate 241 (see Fig. 2). Vertical adjustment of the lace measuring bar 149 bodily is effected by means of a manually operated adjusting lever 246 which, as best shown,

in Fig. 2, is supported to turn on a pivot pin 248 supported by the scale plate 241 and an auxiliary supporting plate 250 secured to the lace measuring bar carrying post 236. The adjusting lever 246 extends across the portion of the plate 241 opposite the scale 240 and is held in adjusted position with relation thereto by means of a spring detent 252 which frictionally engages with a series of serrations 254 formed on the plate 241. A laterally extending arm of the vertical adjusting lever 246 is connected by means of a link 256 with a lug 258 on a vertical plate 260 secured to the post 236.

Further in accordance with the invention, the lace measuring bar 149 is mounted to be readily removable to permit a plurality of such lace measuring bars of different lengths to be interchangeably employed in the machine for the eyeletting and lacing of different types of shoe. It has been found, for example, that with the Blucher type of shoe in which the shoe is assembled on a last with the sides of the lacing slit in substantially parallel relation, a long measuring bar is required which extends over the outer fin in order to measure the length of the lacing which is preferably placed in the eyelets formed at the throat of the lacing slit. With a Bal type of shoe, on the other hand, in which the upper is assembled on a last with the sides of the lacing slit close together at the base and spread out toward the upper end, a relatively short lace measuring bar is preferred since no regulation of the lacing inserted through the eyelets at the base of the lacing slit is required and the adjustment of the lace measuring bar is such as to cause the tip of a full-length lace measuring bar to interfere with the outer fin. For ready removal and replacement of the lace measuring bar 149, the bar is provided intermediate its length with a transverse bearing pin 262 which is arranged to drop into a recess or transverse slot 264 formed at the outer end of arm 234. The upper end of the lace measuring bar is holed to receive a pivot pin 266 carried on a spring plate 268, secured to the arm 234 and arranged for the free position of the spring to pass through the hole in the measuring bar and through an aligned hole in the arm 234. The arrangement above described and illustrated is such as to cause the lace measuring bar to rest normally in its adjusted position as determined by the angular adjustment of the arm 234. However, the lace measuring bar is free to move upwardly about the pivot pin 266 in the event that the arm is engaged while portions of the work support are supported thereon during the feeding movements of the work support outwardly at either of the eyeletting or lacing stations of the machine. With the construction shown, all of the pivoted connections are made very loosely so that the lace measuring bar will be free to drop downwardly again to its normal position so that a minimum risk exists that the bar will remain in its raised position and be brought into interfering engagement with outlying portions of the lacing mechanism during the indexing movement of the work support away from the eyeletting station and to and from the lacing station of the machine.

The invention having been described what is claimed is:

1. A workholder for use in a machine for lacing shoe uppers which comprises a workholding member having clamping devices for clamping the lacing margins of an eyeleted shoe upper in an opened-out edge-facing relation for the placing of groups of enchain lacings through the eyelets of successive pairs, a lace measuring bar around which said groups of interchained lacings are placed, a lacing bar support post mounted upright on the workholding member for adjustment axially to shift the lacing bar bodily toward and away from the clamped upper, a support lever on which the lacing bar is carried pivoted from the post for adjustment angularly to vary the incline of the lacing bar to the clamped upper along the length of the lacing margins, and means under the control of the operator for adjusting said post and the angular relation of the support lever to the post.

2. A workholder for use in a machine for lacing shoe uppers which comprises a workholding member having clamping devices for clamping the lacing margins of an eyeleted shoe upper in an opened-out edge-facing relation for the placing of groups of interchained lacings through the eyelets of successive pairs, a lace measuring bar around which said groups of interchained lacings are placed, a lacing bar support post mounted on the workholding member for adjustment axially to shift the lacing bar bodily toward and away from the clamped upper, a support lever on which the lacing bar is carried pivoted from the post for adjustment angularly to vary the incline of the lacing bar to the clamped upper along the length of the lacing margins, a manual controller movably supported on the post, and connections between the post and support on the workholding member controlled by said controller for adjusting the vertical position of the post, a second manual controller movably supported from the post connected with said support lever for adjusting the angular relation of the support lever and lacing bar thereon with relation to the post.

3. In a machine for lacing shoe uppers, the combination of a workholder on which the upper is supported with the lacing margins in an opened-out edge-facing relation, and a lace measuring device on the workholder comprising a lacing finger support member, devices for supporting said member on the workholder for vertical and for angular adjustment relative to the workholder, a thread lacing finger, a pivotal connection between the member and one end of the finger, on which the finger is movable between a depressed lace measuring position and a raised inoperative position, and a rest on the mem-

5
10

15

20
25
30

ber against which the finger is engaged for the depressed lace measuring position of the finger.

4. In a machine for lacing shoe uppers, the combination of a workholder on which the upper is supported with the lacing margins in an opened-out edge-facing relation, and a lace measuring device on the workholder comprising a vertically adjustable post carried on the workholder, a lacing finger support member pivotally mounted from the post, manual controllers for adjusting the vertical position of the post and the angular position of said member thereon, a lacing finger, a pivot on to which the measuring finger is connected at one end to turn freely between a depressed lace measuring position and a raised inoperative position, and a rest surface on said member against which the finger is supported in a depressed lace measuring position.

5. In a machine for lacing upon shoe uppers, the combination of a workholder comprising a pair of clamping elements between which the upper is supported with the heel portion of the upper encircling one of said elements and with the lacing margins of the upper in an opened-out edge-facing relation, and a lace measuring device on the workholder comprising a lacing finger support member, a cord lacing finger, said support and finger being formed to provide a readily disconnectable pivotal connection between the member and said finger about which the finger is movable between a depressed lace measuring position and a raised inoperative position, and cooperating abutments on the support and finger to limit the downward movement of the finger in said lace measuring position.
